APRON

Filed May 28, 1930

FIG. 1.

By ADA QUINN
Chas K Davies Attorney

Inventor

UNITED STATES PATENT OFFICE

ADA QUINN, OF OGDEN, UTAH

APRON

Application filed May 28, 1930. Serial No. 456,502.

My present invention relates to improvements in aprons for personal wear, and of the sleeveless type, employing ties or strings at the back for securing the garment about the hips or waist. The apron of my invention is designed to provide a garment that is comparatively inexpensive in the cost of production; economical in the material used, which may be put on and removed with facility, and which is effective in use, and presents a neat and attractive appearance.

Due to the novel construction and arrangement of parts of the apron, the garment may be conveniently washed, and ironed flat, thus insuring facility in folding the laundered garment and also facility in storing the garment until ready for use.

My invention involves particularly the back of the apron and the arrangement and use of strings in combination with the apron back for securing the apron in place and against lateral displacement.

One of the essential features of the apron involves its construction whereby the same apron may be adjusted to fit persons of varying heights and sizes, thus providing in one size of apron a garment that may be used in lieu of three different sized aprons, with consequent economy in time and material in the manufacture of the aprons.

The patterns, shape and style of the aprons itself may be changed as desired, and the novel back-structure, which forms the essence of my invention, may also be varied, as indicated in my drawings.

In the accompanying drawings I have shown three variations in the back of the apron wherein the back panel is connected to the neck yoke, but otherwise separated from the apron. These drawings illustrate the embodiment of my invention according to modes I have so far devised for the practical application of the principles of my invention.

Figure 1 is a back view of an apron embodying my invention wherein the back panel is attached directly at the back of the neck yoke.

Figure 2 is a back view showing the back panel forming a continuation of the neck yoke.

Figure 3 is a back view showing the back panel connected to the neck yoke or front portion of the apron by shoulder straps.

It will be understood that the drawings illustrate the apron and its parts in conventional manner only, and that, of course, the aprons are made up as work aprons and fancy aprons, in various shapes colors and styles; from various materials or goods, and with or without ornamental features and finish.

In Figure 1 the skirt or body portion is indicated by the numeral 1 and front pockets 2, 2, are indicated by dotted lines. The bosom or front portion of the apron is designated 3, and usual strings 4 are attached at the opposite sides of the apron to be pulled around the hips or waist, and tied at the back of the apron.

The yoke 5 fits around the neck as usual, and the apron is put on by slipping it over the head, so that the yoke rests upon the shoulders of the wearer.

In the type of apron indicated in Figure 1, the back of the apron comprises an oblong panel 6, which, at its upper end is stitched or otherwise attached to the lower rear edge of the neck yoke.

The edges of the apron, including also the yoke and back panel, are bound with braid or tape as 7.

In all forms of the apron, the panel drops from the shoulders a sufficient length to permit adjustment of the apron to wearers of various sizes, thus adapting a single apron for use by one or a number of persons, and preserving at the same time, the neat appearance of the apron. The apron is thus especially adapted for use in factories, hotels, hospitals and other places where the aprons are used in large quantities, and a neat and attractive appearance is necessary, and these large quantities of aprons are capable of being laundered smoothly and at low cost.

At the lower end of the panel are arranged a plurality of pairs of string-holes 8, the holes in pairs extending across the panel and designed for use with the strings 4. The string-holes are bound with braid or edge tapes 7, the tape being twisted and flattened at 9 in

the center of the panel to reinforce the binding around the holes.

In fastening the apron about the hips or waist, the strings are brought back and around the hips; the free ends of the strings are then passed through adjoining holes of a selected pair of holes, and the usual bow knot is tied in the strings.

One of the three pairs of string-holes may be selected to suit the desires of the wearer of the apron, and it will be apparent that when the strings are tied back, the panel is held in proper position, and the skirt and bosom of the apron are also retained in proper place, the yoke being used to suspend the garment from the shoulders.

In Figure 2, the yoke 10, which is extended from the bosom 11 of the apron is fashioned of two pieces of material, and these pieces of material are fastened together, as by stitches along the seam S, to form the back panel 12 as a continuation of the neck yoke.

The panel 12 is provided with braid or tape, which is employed about the holes 8 in the two pieces of material, and the tape is folded and flattened at the center of the panel to form the pair of holes for the strings.

In the type of apron indicated in Figure 3, the bosom or front 13 of the apron is formed with a front half-yoke or cut out part 14, and a pair of shoulder straps 15 are attached at the shoulder edges of the front. The ends of the straps are attached at the upper end of the back panel 16, and the panel is provided with pairs of holes 8 each bound with a tape or braid for reinforcement.

The string holes, of course, may be of any desired shape, to suit varying conditions, and as indicated in the conventional drawings the panels or back of the apron may be of various shapes, in each instance, however, the uppermost pair of holes is approximately on a line with the attached apron strings for use by a short-waisted wearer, while the two lower pairs of holes are adapted for persons with longer waists. The neck portions of the aprons are fashioned with sufficient fullness so that the back panel may be adjusted to a desired height with relation to the apron strings to insure a neat appearance when the strings are tied.

Having thus fully described my invention, what I claim as new and desire to secure by Letters Patent is:—

55. 1. The combination in an apron adapted for use in various sizes, of a single, permanent, central back panel connected only at the neck portion of the apron, strings attached at the opposite rear sides of the apron, and 60 the panel formed with a plurality of string-holes on each side of its longitudinal center, one of which may be used with each string of the apron.

65. 2. The combination with an apron adapted for use in various sizes, of a permanent,

single, central panel connected only at the neck portion of the apron, a pair of strings attached at the opposite rear sides of the apron, and the panel formed with a series of spaced pairs of string-holes, said pairs comprising holes spaced laterally in the panel.

70 3. The combination in an apron having a neck yoke, and substantially open at the rear, of a permanent, single, central, back-panel suspended only from the rear of the neck yoke, strings attached at opposite rear sides of the apron, and said panel having a pair of string holes at its free end spaced a fixed distance apart for use in fastening the apron by its strings.

75 In testimony whereof I affix my signature.
ADA QUINN.
